United States Patent Office

Des. 226,981
Patented May 22, 1973

226,981

SPOON OR SIMILAR ARTICLE

Ellen B. Manderfield, Syracuse, N.Y., assignor to
Oneida Ltd., Oneida, N.Y.

Filed June 15, 1972, Ser. No. 263,189

Term of patent 14 years

Int. Cl. D7—03

U.S. Cl. D54—12 A

FIG. 1

FIG. 2

FIG. 3

FIG. 4

FIG. 5

FIG. 1 is a front view of a spoon showing my new design;

FIG. 2 is a rear view thereof;

FIG. 3 is a side view thereof, the undisclosed side being substantially identical with the side shown in FIG. 3;

FIG. 4 is an enlarged cross-section taken on line 4—4 of FIG. 1; and

FIG. 5 is an enlarged cross-section taken on line 5—5 of FIG. 1.

I claim:

The ornamental design for a spoon or similar article, substantially as shown and described:
